UNITED STATES PATENT OFFICE.

JOB S. GAWETT, OF TROY, NEW YORK.

SKIRT-IRONING MACHINE.

1,178,148.

Specification of Letters Patent.

Patented Apr. 4, 1916.

Application filed March 5, 1915. Serial No. 12,418.

To all whom it may concern:

Be it known that I, JOB S. GAWETT, a citizen of the United States, residing at Troy, county of Rensselaer, and State of New York, have invented certain new and useful Improvements in Skirt-Ironing Machines, of which the following is a specification.

The invention relates to such improvements and consists in the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of a skirt-ironing machine embodying my invention. Fig. 2 is a top plan view of the padded roll and the ironing-shoe broken away from the rest of the machine. Fig. 3 is a vertical cross-section taken on line 3—3 through the roll-supporting shaft showing in elevation the inner end of the roll and ironing-shoe. Fig. 4 is a view in front elevation of the roll and ironing-shoe. Fig. 5 is a vertical cross-section of the same taken on the broken line 5—5 in Fig. 1. Fig. 6 is a detail in elevation illustrating the manner of operating the roll-supporting shaft to cause a pressing movement between the roll and the shoe.

The principal object of the invention is to adapt an ironing-machine for ironing skirts, nightdresses and similar garments, which have greater fullness at one end than at the other, that is, the bodies of which are tapered.

Referring to the drawings wherein the invention is shown in preferred form, 1 is the frame of the machine upon which is rotatively mounted a shaft, 2, having a gear, 3, fixed thereon meshing with a pinion, 4, in fixed relation to a pulley, 5, adapted to receive a driving belt, not shown.

A roll-supporting shaft, 6, is rotatively mounted substantially parallel with, and obliquely below, the shaft, 2, an intermediate portion of said shaft, 6, passing through a bearing-box, 8, slidably mounted in a slotted bearing, 9, in the frame of the machine, said slotted bearing being substantially perpendicular to the shaft, 2.

A frusto-conical roll or drum, 10, is fixed upon the projecting end of the shaft, 6, out-

side the frame of the machine, and the other end of the shaft, 6, has a rocking-bearing upon the frame of the machine at 11, which permits the shaft to be rocked toward and from the shaft, 2, by movements of the bearing-box, 8, along the slot, 9.

A gear-wheel, 12, fixed upon the shaft, 6, is adapted to be moved by the rocking movement of said shaft into and out of engagement with a pinion, 13, on the shaft, 2.

The bearing-box, 8, is adapted to be moved along the slideway, 9, toward the shaft, 2 by means of a lever, 14, pivoted at 15, upon the frame of the machine, and having one end engageable with a lug or offset, 16, on said bearing-box, 8, the other end of said lever being connected by a link or rod, 17, with a treadle, 18. By depressing the treadle, 18, the shaft, 6, can be rocked toward the shaft, 2, to cause the gear, 12, and pinion, 13, to intermesh, and when the treadle is released, the weight of the shaft, 6, and roll, 10, will cause a return rocking movement of the shaft, 6, to separate the gear, 12, from the pinion, 13.

The frusto-conical drum or roll, 10, tapers outwardly and may be padded in the usual manner.

An ironing-shoe, 7, is supported from the frame, 1, by means of brackets, 19, substantially parallel with, and obliquely above, the roll, 10. This shoe is preferably made hollow whereby it is adapted to be heated by steam through the medium of steam-pipes, 20, and is formed with a concaved surface, 21, adjacent to, and conforming to, the frusto-conical surface of the roll 10. The shoe, 7, is also preferably outwardly tapered to substantially the same degree as the roll or drum. The position of the shoe is such that when the treadle, 18, is released, sufficient space will be left between the surface of the roll and the concaved surface, 21, of the shoe, as shown in Figs. 3 and 5, to freely permit the insertion and removal of the garment to be ironed.

The garment to be ironed is placed in the machine by drawing the larger end of the garment inwardly over the smaller end of the roll, 10, and then the treadle, 18, is depressed throwing the gear, 12, into mesh with the pinion, 13, to drive the roll, 10, which roll carries the garment past the concaved ironing surface of the iron, 7, under pressure which is regulated by the treadle, 18. The surface speed of the larger end of

2
the roll, 10, being considerably greater than that of its smaller end, the extra fullness in the larger end of the garment will be substantially taken up in passing the garment around the roll, and the garment will, during the ironing operation, remain symmetrically disposed upon the roll instead of tending to creep off from the roll, as is the case where it is attempted to iron a tapered or flaring garment upon a cylindrical roll. As time and heat are important elements in the ironing operation, I taper the ironing-shoe, 7, to substantially the same degree as the roll, 10, in order that the parts of the garment which travel at the greater speed shall be exposed to the heated concaved surface of the shoe for substantially as long a period as the parts of the garment on the smaller end of the roll.

15 Any known means may be employed for.

rotating the frusto-conical roll and for causing a relative pressing movement between said roll and the ironing-shoe.

What I claim as new and desire to secure by Letters Patent is—

25 In an ironing-machine, and in combination, a frusto-conical roll, and an ironing-shoe extending longitudinally therewith, and having a concaved surface coöperative with one side of said roll, said shoe being longitudinally tapered to correspond with the taper of the roll, and having a roll-engaging surface of the same angular extent throughout its length.

30 In testimony whereof, I have hereunto set my hand this 1st day of March, 1915.

JOB S. GAWETT.
